UNITED STATES PATENT OFFICE.

FRANK W. NELSON, OF SEATTLE, WASHINGTON.

FRUIT-GATHERING LADDER.

Application filed September 3, 1924. Serial No. 735,648.

This invention relates to ladders, and more particularly to an improvement in ladders of the type particularly adapted for fruit gathering.

5 To that end the invention contemplates a ladder, durable and stable in construction and which may be readily handled in the orchard, and which may be also readily placed between the limbs of the tree to 10 permit of more conveniently gathering the fruit without knocking against or otherwise bruising or damaging the same.

Another object of the invention is to provide a construction which permits the fruit gatherer to stand on the ladder with greater comfort and without danger of his foot slipping off the ladder steps.

A further object of the invention is to provide a novel center rail construction which 20 contributes materially to the strength and stability of the construction, and at the same time is provided with an upward extension or continuation which permits of the fruit gatherer steadyng himself while standing 25 on the topmost step.

With the above and other objects in view which will more readily appear as the nature of the invention is better understood, the same consists in the novel construction, 30 combination and arrangement of parts hereinafter more fully described, illustrated and claimed.

A preferred and practical embodiment of the invention is shown in the accompanying 35 drawings in which—

Figure 1 is a side elevation of my improved ladder.

Figure 2 is a front elevation thereof.

40 Figure 3 is a detail sectional view taken on the line 3—3 of Figure 2.

Figure 4 is a horizontal sectional view taken on the line 4—4 of Figure 2.

Figure 5 is a sectional view taken on the line 5—5 of Figure 4.

45 Figure 6 is a sectional view taken on the line 6—6 of Fig. 1.

Fig. 7 is a fragmentary edge elevation of a platform step used in the ladder structure and attached parts.

50 Similar reference characters designate corresponding parts throughout the several figures of the drawings.

As previously indicated, it is desirable to have a ladder as light as possible to facilitate its movement from place to place in the

orchard and yet at the same time the light construction must possess adequate stability and strength.

Therefore, with a view to obtaining the desired lightness it is proposed to construct 60 the ladder mainly of wood and to that end I provide a novel center rail designated generally as C and preferably comprising a relatively long narrow body 1 formed of a plank of wood of suitable length and thickness and having secured to its rear edge 2 a flat reinforcing strip 3, the same being screwed or nailed to the edge 2 for the purpose of stiffening the member 1 against 65 flexibility, and thereby providing in effect 70 a wooden beam of T-shaped cross section. The lower end of this center rail does not extend to the ground but is supported by a frame designated generally as F. The member 1 is also provided at preferably equidistant points with laterally offset or 75 projecting steps or foot rests designated generally as S and having novel features of construction which will be presently referred to more in detail.

80 Referring first to the frame F it will be observed that the same preferably consists of the cross bars 4 and 5, the former being set into a mortise in the exposed edge of the member 1 and secured thereto by suitable 85 fastenings 6, and the cross bar 5 consisting of duplicate bar members 5^a and 5^b which are set into suitable mortised portions of the member 1 as indicated in Figures 1 and 3. The outer ends of the members 4, 5^a and 5^b are connected to the converging leg members 7 and 8 whose lower ends rest upon the ground to thereby support the center rail C while the upper ends thereof are provided 90 with brackets 9 for engaging with the fastening which holds the second step members S to the member 1. This arrangement provides a thoroughly braced center rail and because of the fact that the members 7 and 8 extend well up on the center rail, the same 95 is adequately braced against side rocking and gives anyone standing on the ladder a sense of security that would not otherwise be possible if the center of gravity were not lowered, by the arrangement just described.

100 The steps S are preferably made of blocks of wood 10 and each pair of blocks is connected by a through-bolt 11, the said bolt extending through both of the blocks 10 and also through the web provided by 110

the member 1, thereby securely holding the blocks in place, but to further assist in strengthening the entire structure, the blocks may be also nailed or screwed to 5 the reinforcing strip 3 by the fastenings 12 as shown in Figure 4. The upper surfaces of the blocks 10 are preferably inclined inwardly toward the member 1 so as to prevent foot-slipping, thereby further adding 10 to the sense of security to the fruit gatherer while he is at work on the ladder.

The top of the center rail is extended as indicated at 1^a beyond the reinforcing member 3, thereby to provide a steady 15 post at the top of the ladder so that when the fruit gatherer is on the topmost step of he ladder he will be afforded a convenient handhold thereby to enable him to reach out after fruit without losing his balance.

20 The third leg of the ladder is designated as T and is pivotally connected to the top step 13 which is in the form of a relatively wide platform as compared with the lower steps S and is notched or recessed as indicated at 14 to receive the upper end of 25 the leg T. As shown in Figure 6 the top step 13 is secured to the center rail C by means of the bolts 15, thereby making the top step strong and steady while the third 30 leg T is pivotally connected to the edge of the step 13 by the relatively long bolt 16 which in turn serves to clamp the eyes 17 of the braces 18 to the opposite ends of the step. These braces have their lower ends 35 fastened as at 19 to the shank portion of the third leg T and thereby strengthen and

stiffen the leg T at its point of connection with the step 13.

From the foregoing it is thought that it will be apparent that the present invention 40 provides a light durable and stable construction that may be readily transported and which may be easily placed between the leads or limbs of the tree without materially interfering with the fruit while at the 45 same time giving the fruit gatherer firm support and enabling him to more expeditiously accomplish his work.

I claim:—

A ladder comprising a centrally disposed 50 rail, a strip applied to the rear edge of the lower portion thereof, said strip having side edge portions which extend beyond the side surfaces of the rail, a platform step mounted upon the upper end of the strip 55 and having a recess which receives the rail, a prop leg pivoted to the platform step, a series of steps applied to the intermediate portions of the rail and the strip, spaced bars applied to the lower end of the rail and at the the opposite sides thereof, one of said bars being secured to the lower end of the strip, and leg members secured at their upper ends to the outer ends of certain of the intermediately located steps and having 60 their intermediate portions disposed between the spaced bars at the ends thereof and secured thereto.

In testimony whereof I hereunto affix my signature.

FRANK W. NELSON.
